UNITED STATES PATENT OFFICE.

WILLIAM L. BARRON, OF NEW YORK, N. Y., ASSIGNOR TO THE SINGER MANUFACTURING COMPANY, A CORPORATION OF NEW JERSEY.

THREAD-CUTTING MECHANISM FOR SEWING-MACHINES.

1,228,871.

Specification of Letters Patent.

Patented June 5, 1917.

Application filed February 7, 1913. Serial No. 746,696.

To all whom it may concern:

Be it known that I, WILLIAM L. BARRON, a citizen of the United States, residing at New York, in the county of New York and 5 State of New York, have invented certain new and useful Improvements in Thread-Cutting Mechanisms for Sewing-Machines, of which the following is a specification, reference being had therein to the accompanying 10 drawings.

My invention relates to sewing machines and more particularly to an automatic needle-thread nipping and cutting attachment for use in that class of machines which sew 15 detached groups of stitches, such for example as sewing on buttons, tacking, barring, &c., the object of the invention being to provide an attachment to nip and sever the loose end of the needle thread at the beginning of 20 the sewing of the group of stitches, and to sever the needle-thread at the completion of the group of stitches.

The invention will be understood by reference to the accompanying drawings in 25 which Figure 1 is a rear side elevation, and Fig. 2 a bottom plan of a flat button sewing machine of the Singer type; Figs. 3 and 4 bottom plan views of the thread-nipping and severing attachment with the parts in 30 different positions; Fig. 5 a perspective view of the attachment with the parts in position immediately after the cutting of the needle-thread; Figs. 6 and 7 sections on the planes of the lines 6—6 and 7—7 of Fig. 3, respectively; Fig. 8 a perspective view of the thread-nipper and part of the throat-plate; Fig. 9 a similar view of the needle-hole portion of the throat-plate; and Fig. 10 a face view of a portion of the cam for giving 35 movements to the parts of the attachment. Similar reference numerals indicate similar parts in the several views.

For convenience of illustrating one application of the use of the present invention, I 40 have selected a well known form of Singer lock-stitch sewing machine fitted with an attachment for sewing on buttons. As shown, the machine comprises a needle 1 carried by a vertically reciprocating needle-bar operated from the driving shaft 2 which shaft is journaled in the upper part of the arm 3, and an oscillating shuttle fitted within the shuttle-race 4 depending from the bed-plate 5, the said shuttle deriving its operative 45 movements from the driver 6 connected,

through the oscillating shaft 7, to the driving shaft 2. The latter is provided with loose pulley 8 and fast pulley 9, the fast pulley having an integral or rigidly attached stop-motion cam 10. Pivotedly 60 mounted at its lower end in a projection 11 from the upright portion of the bracket-arm, is a start and stop-motion lever 12 provided with a belt-shifter 13 and with the spring-pressed plunger 14. The stop-motion lever 12 is adapted to assume its rearward or operative position under the action of a spring, and is detained in its forward or inoperative position by a detent-lever 15 fulcrumed at 16 and maintained normally 70 in operative engagement with the upper portion of the stop-lever by means of the spring 17 in a manner well-known. The stop-lever 12 is so mounted within the projection 11 as to be capable of slight side- 75 wise movement which is yieldingly resisted in the stitching operation by the spring-pressed plunger-pin 18, shown in end view only in Fig. 1.

As shown in Figs. 3, 4 and 5 the super- 80 posed tapered blades 19 and 20 are fixed upon an arm 21 attached to a sector-gear 22, which gear is journaled upon a pin 23 within a bracket 24 attached to the under side of the throat-plate 25. Meshing with said sec- 85 tor-gear is a rack 26 (see Fig. 2) formed upon a lateral arm carried by the sliding bar 27 supported beneath the work-plate of the machine and having near its rearward end a block 28 with a lateral notch. This notch is 90 entered by the contracted lower end of a lever 29 pivotally mounted upon the fixed fulcrum-stud 30, carried by a bracket 31 attached to the bed-plate 5, and provided at its upper end with a pin or roller-stud 32 95 entering the cam-groove 33 in the rear face of the rotary cam-wheel 34, the latter being mounted upon a fixed stud carried by the frame of the machine. The cam-wheel 34 has attached to its front side, as indicated in 100 dotted lines in Fig. 1, a worm-wheel 35 meshing with a worm 36 fixed upon the main-shaft 2. The block 28 has a rearward extension carrying a pin or roller-stud 37 (see Fig. 2) embraced by the forked arm 38 105 of a bellcrank-lever fulcrumed at 39, and having a second arm 40 provided with a spring-pressed pin 41 entering a slot 42 in the lower end of stop-lever 12.

The lever 29 and bellcrank-lever 38—40 110

serve, through the connections above described, to impart a plural-stage movement to the thread-cutters 19 and 20 at the end of each series of stitch-forming operations, 5 whereby needle and shuttle threads are positioned for severing during the final stitch-forming cycle of the series, and are severed by the lateral overthrow of the stop-lever in the final stopping of the moving parts, 10 all as more fully explained in the United States patent to C. M. Horton No. 807,676, dated December 19, 1905. These levers and connections also serve to impart the movements to the needle-thread nipping and cutting attachment at the beginning of each series of stitch-forming operations as will now be described.

As shown in Figs. 3, 4 and 5 the under side of the throat-plate is preferably cut out at 43 to accommodate a spring-pressed jaw 44, pivoted at 45, and normally held out of engagement at its forward end, by the spring 46, with a fixed jaw 47, which latter may be for convenience a separate 25 piece fastened to the throat-plate. Rigidly secured to the arm 21 which carries the lower thread-cutting blade 19 and the needle-thread cutting blade 20, is a thread-carrying arm 48 disposed adjacent the under 30 side of the throat-plate and adapted in its movements to pass over the thread-nipping jaws 44 and 47. At its forward end the arm 48 is formed with a hook or barb 49 which barb, on the initial movement of arm 48, 35 engages the loose end of the needle-thread and draws it between the nipping jaws. On its outer edge the arm 48 is formed with a cam surface 50 which surface, when the parts are in normal position shown in Fig. 3, lies beyond a stud 51 extending laterally from the side of the movable jaw 44 so that said jaw at such time will be open. When the arm 48 is retracted, or moved to the right as viewed in the drawings, the cam surface 50 will engage 40 stud 51 immediately after the barb 49 has drawn the needle-thread between the gripping jaws, and the contact of the cam surface 50 with said stud will hold the jaw 44 closed upon the needle-thread. The barb 49 forms one member of a shearing or cutting mechanism, the other member consisting of a blade 52 in the form of a flat plate having a notch 53 located a short distance to one side of the gripping faces of the jaws 44 and 47. The cutting blade 52 lies directly under the plane of movement of arm 48, that is these two parts are substantially in engagement with each other whenever the arm 48 is moved over the blade 52 (Figs. 50 6 and 7). As explained hereinafter, after the arm 48 has drawn the thread between the nipping jaws and the latter have closed upon the needle thread, the further travel of arm 48, on its initial movement, will sever 65 the loose end of the thread by drawing it

across the blade 52, and then a dwell in the actuating cam will hold arm 48 in fixed position, as shown in Fig. 4, to hold the jaws closed for a predetermined number of stitches.

The cam 34 may be geared so that the machine will sew one, two, three or more groups of stitches for one revolution of the cam. In the machine illustrated, the cam is geared 1 to 42, and the cam-groove 33 is 70 so divided as to sew three groups of fourteen stitches each. One of the sections over which the stud or cam-follower 32 travels to effect the desired movements of blades 19 and 20 and arm 48 is shown on an enlarged scale in Fig. 10. Upon the completion of a group of stitches the parts above described as under the throat-plate are in the positions shown in Fig. 3, that is, with the barb 49 at the left of the needle-hole 54. At such time the cam-follower 32 is on the dwell 55. When the machine is started the needle descends, the loose end of the needle thread being above the work-plate. As the needle begins to rise the thread-loop thus formed is seized by the point of the shuttle and extended sufficiently for the latter's passage, slack being provided for such operation by the partial descent of the take-up arm in this stage of the stitch-forming cycle. The 90 passage of the shuttle through the loop of needle thread draws the loose end of the thread down through the needle-hole. As the take-up rises, cam-follower 32 travels over the inclined cam section 56 thereby moving lever 29 and the parts before described as actuated thereby, to move rack 26 to impart an initial rotary movement to sector-gear 22. Cam-follower 32 then passes on to the dwell 57 of the cam-groove. The 95 movement of sector-gear 22 will swing arm 48 so that its barb 49 will cross the needle-hole 54 in a path beneath the movable and fixed jaws 44 and 47 thereby engaging the loose end of the needle thread and drawing the latter to one side, as shown in Fig. 7, and between the nipping jaws 44 and 47. When the thread is so placed, cam surface 50 will engage pin 51, closing the jaw 44 upon jaw 47 to thereby firmly grip and hold 100 the thread between said jaws. The movement of arm 48 continues while follower 32 is on the cam section 56, and this further travel will effect the cutting of the thread between the barb 49 and blade 52, as indicated in Fig. 7. Arm 48 remains in substantially the position shown in Fig. 4 while the follower 32 is on the dwell 57 of cam 34, and in this position the cam surface 50 of 105 said arm, by bearing against pin 51, will hold the end of the needle-thread gripped between the jaws 44 and 47. In practice dwell 57 will be made long enough so that the machine will sew two, three or more 110 stitches as may be desired before follower 115

32 leaves the dwell. In the machine illustrated two stitches will be made while the cam-follower is on dwell 57.

When cam-follower 32 reaches the inclined section 58 of the cam-groove, sector-gear 22 will be given a second movement through the described connections, to thereby impart a further movement to arm 48 in the same direction as it was moved when the 10 said follower was passing over the inclined section 56. This second movement carries the parts to the position shown in Fig. 5, that is, to the extreme right, where they remain as long as follower 32 is on the dwell 15 59. In this movement the cam surface 50 passes out of contact with pin 51 and as a result jaw 44 is opened by a spring 46. It is to be understood that blades 19 and 20 being rigidly secured to arm 21 will also 20 take the position shown in Fig. 5, to be moved forward at the close of the stitching cycle to sever the lower and the needle threads.

Assuming for the purpose of describing 25 the operation of the machine that cam 34 makes but one revolution for each group of stitches, the cutting blades and arm 44 will remain in the position shown in Fig. 5, while the machine sews the stitches in the particular work for which it is adapted, that is, button sewing, tacking, barring, &c., that is, while the follower 32 is on dwell 59. When the follower reaches the cam or inclined section 60, blades 19 and 20 will be advanced 30 sufficiently to enable the former to engage the lower or shuttle thread. These blades will then have a short period of rest while the follower is on the short dwell 61, and then moved so that, on the next descent of 40 the needle, blade 20 will engage the needle-thread loop, and the two threads will be severed by the overthrow of the stop-lever when follower 32 reaches dwell 55 opposite the enlarged depression 62. That is, the 45 blades 19 and 20 will be given a quick movement to their extreme forward position to sever the threads and then restored to normal position shown in Fig. 3, as fully described in Patent No. 807,676, before referred to, and in patent to C. M. Horton, No. 1,001,034, dated August 22, 1911. In these movements of blades 19 and 20, at the 50 close of the stitching cycle, arm 48 will also be moved, crossing the needle-hole 54 after the needle-thread has been severed, and then assuming its normal position shown in Fig. 3. In such position the nipping jaws are open.

While I have described the cutting blades 60 19 and 20 they form no part of the present invention, the latter being confined to the described mechanism for successively nipping and cutting the needle-thread, and then holding the end of the needle-thread for a 65 predetermined period at the beginning of

the stitching cycle. It is to be understood that one of the chief objects of the improvement as thus described is to effect a uniformity of the finished work unattainable by mechanism heretofore in use. By means of 70 the present mechanism, the loose ends of the needle-thread left below the fabric are invariably cut off close to and at the same distance from the lower face of the fabric, thereby obviating the necessity heretofore 75 existing of clipping such loose thread ends by hand.

As will be observed, the action of the cam surface 50 upon the stud 51 causes a practically positive gripping action of the nipping jaws upon the thread, so that any pull upon the latter in the shearing action of the blade 52 and arm 48 is effectively resisted by the nipping and a clean cut is thereby insured, producing a uniform thread-end attached to the fabric. 80

Having thus set forth the nature of the invention, what I claim herein is:—

1. In a sewing machine in combination, a reciprocating needle and complemental 90 stitch-forming mechanism, and mechanism for successively nipping the needle thread and severing the loose end at the beginning of a stitching cycle, said mechanism including a thread-drawing member and a nipping 95 element moving relatively to and actuated by said thread-drawing member.

2. In a sewing machine in combination, a reciprocating needle and complemental 100 stitch-forming mechanism, and mechanism for successively nipping the needle thread and severing the loose end at the beginning of a stitching cycle, and for holding said thread for a predetermined time after the loose end has been severed, the nipping device of said mechanism being mounted independently of the severing means. 105

3. In a sewing machine, in combination, a reciprocating needle and complemental 110 stitch-forming mechanism, thread-severing mechanism, thread-nipping mechanism comprising a nipping wall and a nipping jaw independent of the severing mechanism and moving in a plane intersecting the said nipping wall, the said severing and nipping 115 mechanism acting upon the thread to successively nip the same below the work-plate at the beginning of a stitching cycle, then to cut the loose end of said thread and to hold the end of the thread for a predetermined 120 period.

4. In a sewing machine, in combination, a reciprocating needle and complemental 125 stitch-forming mechanism, a thread-nipping device comprising a movable jaw and a jaw coacting therewith, a thread-drawing member movable in a path entirely outside of the range of action of said jaws for drawing the needle-thread between said jaws, and means for closing said jaws upon the 130

thread and holding them closed for a predetermined period.

5. In a sewing machine in combination, a reciprocating needle and complemental 5 stitch-forming mechanism, a thread-nipping device comprising a movable jaw and a jaw coacting therewith, means movable relatively to said jaws for drawing the needle-thread between the same, means for closing 10 said jaws upon the thread and holding them closed for a predetermined period, and means for cutting the loose end of the thread while it is so held.

6. In a sewing machine in combination, 15 a reciprocating needle and complemental stitch-forming mechanism, a needle thread nipping device comprising a movable jaw and a jaw coacting therewith, an arm and means for moving the same to cause it to engage and draw the thread between said jaws, a cam surface on said arm adapted to engage one of said jaws to close it upon the other after the thread has been drawn between them, and means for holding the jaws 25 closed for a predetermined time.

7. In a sewing machine in combination, a reciprocating needle and complemental 30 stitch-forming mechanism, a thread-nipping device comprising a movable jaw and a jaw coacting therewith, a member movable relatively to said jaws and means to actuate the same to engage and draw the needle-thread between said jaws during a portion of its travel, and to effect the cutting 35 of the loose end of the thread upon its further travel.

8. In a sewing machine in combination, a reciprocating needle and complemental 40 stitch-forming mechanism, a needle thread nipping device comprising a movable jaw and a jaw coacting therewith, an arm and means for moving the same to cause it to engage and draw the thread between said jaws, a cam surface on said arm adapted to engage one of said jaws to close it upon the other after the thread has been drawn between them, means for severing the loose 45 end of the thread while it is so held, and means for holding the jaws closed upon the thread for a predetermined time after the loose end has been severed.

9. In a sewing machine in combination, a reciprocating needle and complemental 55 stitch-forming mechanism, a thread-nipping device comprising normally open jaws, a needle-thread engaging arm and means for moving the same to engage said thread and draw it between said jaws, means for closing said jaws upon the thread, and a thread-cutting blade to effect the cutting 60 of the loose end of the thread upon the further travel of said arm.

10. In a sewing machine in combination, 65 a reciprocating needle and complemental stitch-forming mechanism, a thread-nip-

ping device comprising a movable jaw and a jaw coacting therewith, a thread-engaging arm and means for moving the same to engage the needle thread and draw it between said jaws, said arm having a cam surface to close said jaws after the thread is drawn between them, and a cutting blade in proximity to said jaws to effect the cutting of the loose end of the thread upon the further travel of said arm.

11. In a sewing machine, in combination, a reciprocating needle and complemental 75 stitch-forming mechanism, a thread-nipping and cutting device located beneath the work-plate and adjacent to the point of descent of the needle, a stop-motion device whereby groups of a predetermined number of stitches may be formed, said nipping device comprising normally open jaws, one jaw being movable relatively to the other, a needle-thread engaging arm and means for moving the same to engage and draw the thread between the jaws, means for closing the jaws and for holding them closed to nip the thread for a predetermined period, the further travel of said blade effecting the cutting of the loose end of the thread.

12. In a sewing machine in combination, a reciprocating needle and complemental 80 stitch-forming mechanism, a thread-nipping and cutting device comprising a fixed jaw and a coöperating spring-pressed jaw both below the work-plate, a thread-engaging arm and means for moving the same to engage the needle-thread and draw it between 85 said jaws, said arm having a cam-surface adapted to close the movable jaw upon the fixed jaw, and a cutting blade in proximity to said jaws to effect the cutting of the loose 90 end of the thread upon the further travel of said engaging arm.

13. In a sewing machine, in combination, 95 stitch-forming mechanism, including a reciprocating needle, a fixed cutting blade, a thread-drawing and cutting element coöperating with said fixed blade, a blade movable to cut the thread independently of said fixed blade, and means for imparting to said movable blade and thread-drawing element successive operative movements to cut the 100 needle-thread at different points.

14. In a sewing machine, in combination, 110 stitch-forming mechanism including a reciprocating needle, two thread-cutting members movable in unison and adapted for action upon the thread, and means for imparting to said thread-cutting members a cutting movement at the completion of one group of stitches and another cutting movement at substantially the beginning of 115 the production of another group of stitches of predetermined number to cause said members to sever the needle-thread successively in different stitch-forming cycles.

15. In a sewing machine, in combination, 120

stitch-forming mechanism including a reciprocating needle, a movable cutting blade, a fixed cutting blade and a thread-drawing member adapted to coact therewith, and an actuating cam and a connection including a common element between said cam and the movable blade and thread-drawing member whereby successive operative movements are imparted to said blade and member for cutting the thread at different points.

16. In a sewing machine in combination, stitch-forming mechanism including a reciprocating needle, two thread-cutting devices and a nipping device, comprising a jaw movable in a plane intersecting a coacting nipping surface, all adapted for action upon the needle thread, and means for actuating said thread-cutting devices successively in cutting the needle thread at different points and for actuating the nipping device to nip the needle thread intermediate the cutting actions.

17. In a sewing machine, in combination, stitch-forming mechanism including a reciprocating needle, two thread-cutting members movable in unison and adapted for action upon the thread, and means for impart-

ing to said thread-cutting members a cutting movement in one direction at the completion of a group of stitches and another cutting movement in the opposite direction at substantially the beginning of the production of another group of stitches of predetermined number, to cause said members to act upon the needle-thread successively in different stitch-forming cycles.

18. In a sewing machine for forming a predetermined number of stitches, the combination with stitch-forming mechanism, of movably mounted thread-severing means, and automatically operated mechanism for moving said thread-severing means to trim off the beginning end of the needle-thread during the first part of a stitching operation and to sever the needle-thread at the end of a stitching operation.

In testimony whereof, I have signed my name to this specification, in the presence of two subscribing witnesses.

WILLIAM L. BARRON.
